[57] CLAIM

The ornamental design for a pocket radio with display area, as shown and described.

DESCRIPTION

FIG. 1 is a perspective view of a "pocket radio with display area" showing my new design;

FIG. 2 is a top plan view thereof;

FIG. 3 is a front elevational view thereof;

FIG. 4 is a right end elevational view thereof;

FIG. 5 is a rear elevational view thereof;

FIG. 6 is a left end elevational view thereof; and,

FIG. 7 is a bottom plan view thereof.

The broken lines illustrating a person in FIGS. 1 and 2 are for illustrative purposes only and form no part of my design.
